UNITED STATES PATENT OFFICE.

EUGENE CHILDS, OF BOSTON, MASSACHUSETTS, ASSIGNOR TO THE TRIMONT MANUFACTURING COMPANY, OF SAME PLACE AND PORTLAND, MAINE.

DESIGN FOR A DIE FOR FORGING BODIES OF ROTARY TRIMMER-CUTTERS.

SPECIFICATION forming part of Design No. 30,677, dated May 2, 1899.

Application filed March 29, 1899. Serial No. 711,017. Term of patent 14 years.

To all whom it may concern:

Be it known that I, EUGENE CHILDS, a citizen of the United States, residing at Boston, in the county of Suffolk and Commonwealth 5 of Massachusetts, have invented and produced a new and original Design for a Die for Forging Bodies of Rotary Trimmer-Cutters, of which the following is a specification.

Figure 1 shows my design in face view, and 10 Fig. 2 shows the same in cross-section.

The leading feature of my design for a die consists of a block provided at one of its faces with an annular cavity having its outer wall inclined inwardly toward the bottom of said 15 cavity, and a centrally-recessed projection in said cavity.

The block representing my design is provided at one of its faces with an annular

cavity a' , having its outer wall a' inclined inwardly toward the bottom of said cavity, and 20 a centrally-recessed projection a^3 , the recess being designated a^4 .

Having fully described my design, what I claim as new, and desire to secure by Letters Patent, is—

The design for a die for forging bodies of rotary trimmer-cutters, substantially as shown and described.

In testimony whereof I have signed my name to this specification in the presence of 30 two subscribing witnesses.

EUGENE CHILDS.

Witnesses:

GEO. W. GREGORY,
MARGARET A. DUNN.
